UNITED STATES PATENT OFFICE.

CHRISTOPHER J. M. WEBER AND AXEL OLSON, OF ST. PAUL, MINNESOTA.

MAIL-POUCH CATCHING AND DELIVERING DEVICE.

Application filed June 15, 1922. Serial No. 568,519.

To all whom it may concern:

Be it known that we, CHRISTOPHER J. M. WEBER, a citizen of the United States, and AXEL OLSON, a subject of the King of Sweden, both residing at St. Paul, in the county of Ramsey and State of Minnesota, have invented certain new and useful Improvements in Mail-Pouch Catching and Delivering Devices, of which the following is

10 a specification.

This invention relates to mail pouch catching and delivering devices for use in connection with railway mail coaches, and has for its principal object to provide simple and efficient mail catching and delivering means which is automatically actuated at the proper time, concurrently with the movement of the train.

Devices of the class described, wherein the judgement of the attendant is relied upon for the selection of the proper moment to operate the catching and delivering mechanism, are objectionable because of the difficulties encountered in darkness or fog, the ever prevailing uncertainty and danger of premature or late operation, and the possible laxness on the part of the attendant.

It is an object of the invention to provide in devices of this class, improved means whereby the catching and delivering mechanism is co-operatively connected and automatically actuated at a definite point along the track, and is capable of being readily rendered inoperative when the mail coach is out of service.

A further object of the invention is to provide in a device of the class described, mechanism adapted to be operated from a stationary member placed on the track, embodying certain novel features of construction, whereby this mode of operation is rendered practically free from the danger of accident, the mechanism, also, including provision to compensate for the constantly varying lateral position of the car body relative to the track, whereby the mail catching arm and delivering devices are controlled at all times to be moved to a definite operative position.

50 Other objects and advantages will be pointed out as this specification progresses, the invention consisting in the features of

construction, combination and arrangement of parts hereinafter to be described and specifically claimed.

55 In the accompanying drawings, forming part of this specification:—

Figure 1, is a fragmentary perspective view of a railway mail coach and railway track showing our improved device applied thereto.

Fig. 2, is an end elevation of Figure 1, drawn to a reduced scale showing partly in diagram certain parts of the invention in operative position.

65 Fig. 3, is a plan view of a portion of a railway track showing the stationary member, forming part of the invention, positioned thereon, and also the position of the mail pouch standard relative thereto.

70 Figs. 4 and 5, are views of parts of the lever mechanism belonging to the delivering portion of the invention showing it in operative and inoperative position, respectively.

Fig. 6, is a perspective view of the clutch mechanism for arbitrarily rendering the invention inoperative.

75 Figs. 7, and 8, are views of details forming parts shown in Figure 6.

Fig. 9, is a side elevation of the hand lever for operating the clutch shown in Figure 6.

80 Fig. 10, is a perspective view of the slide bar forming part of the pouch catching hook.

85 Fig. 11, is a longitudinal cross section of the casing surrounding the slide bar shown in Figure 10.

Fig. 12, is a sectional view on line 12—12 of Figure 11.

90 Fig. 13, is an end view of Figure 11.

Fig. 14, is a fragmentary perspective view of one of the pouch supporting members of the delivering mechanism.

95 Fig. 15, is a detail thereof, and

Fig. 16, is a side elevation of the formation of the end of the stationary rail member.

100 In the drawings, 1 designates the floor of a railway mail coach, 2 the nearside wall thereof, 3 and 3' the right and left door jambs of the door opening, and 4 the door sill. The car body is supported in the usual manner (not shown) by the truck wheels 5,

which in turn traverse the usual rails 6 and 6'. Arranged between the rails and in parallelism therewith and located nearer the rail 6 thereof, is the impact or cam rail 7. This cam rail is mounted on the sleepers 7', to bring its tread an appreciable distance (about two inches) above the level of the tread of the rail 6. At its ends the cam rail (which may be termed a stationary member) is bent in a curve in a horizontal plane extending outwardly toward the rail 6, to a point indicated by dotted lines *a* (Figs. 3 and 16) and then downwardly in a curve to bring its outer extremity below the top of the main rail 6. The object of bending the outer extremities of the rails so as to dip below the top of the main rails, is to obviate the formation of an abrupt shoulder above the main track, which would constitute a source of danger.

Firmly secured to the underside of the floor of the car are the frame members 8 and 8'. The frame members are arranged side by side longitudinally of the car body, and are formed with journal bearings 8" wherein is journaled the shaft 9, the inner end of the shaft having further journal support 9' which latter forms part of the frame member 10, also secured to the bottom of the floor of the car body. Thus, the frame members 8 and 8' and 10 constitute collectively a frame.

The shaft 9 extends transversely of the cam rail and is slideable longitudinally in said journals. Carried by the shaft and longitudinally adjustable thereon, as by means of the set screws 10' is the cam wheel 11, the periphery thereof being V-shaped to present a central peripheral knife edge, the sloping outer side of said knife edge being adapted to engage with the curved inner sides respectively of the ends of the cam rail 7 when traveling in either direction, as is best shown in Figure 3 of the drawings.

An extensible spring 11' which surrounds the shaft 9 and extends between the cam wheel and the frame member 8' holds the cam wheel under stress against the rail, when the device is in operation. A collar 11" at the inner end of the shaft constitutes adjustment means, whereby the sliding movement of the shaft may be selectively restricted. Thus, when the car is traveling in either direction, and the cam wheel is properly adjusted on the shaft, it will engage with the curved ends of the impact rail at a tangent, the inclination of the sides of the knife edge of the wheel being made to conform to the general angularity of the curvature of the inner curved faces of the rail, the movement of the car causing a rotary camming action of the wheel on the rail to effect a sliding movement of the shaft in its journal. As the cam wheel

leaves the rail 7 it will noiselessly, under the influence of its spring, engage the curved end to return to its normal inoperative position.

The frame member 10 is further provided with a pair of arms (Fig. 1) which form a slideway 12, said slideway extending parallel with the sliding shaft 9, and being adapted to slidably receive the vertical arm 12' extending from the shaft 9 through said slideway and above the latter, and being formed at its upper extremity with a hollow hub 12" adapted to slidably receive the pull rod 13. The arm 12' is formed at its base with an appreciably long hub through which rotatably extends the shaft 9, the arm being adjustable longitudinally on said shaft as by means of the set screwed collars 12'''. The pull rod 13 extends horizontally transversely of the car body and loosely through the hub 12', and carries at its inner extremity a stop collar 13', between which latter and the hub, is the extensible coil spring 13" which surrounds said pull rod. Extending longitudinally of the car body at a point adjacent the outer face thereof, spaced from the underside of the floor of the car, is the rock shaft 14. This rock shaft is supported on the car body by means of end brackets 14', secured to the car body. Suitable collars 14" at the ends of the shaft hold the shaft against longitudinal displacement. Rotatable on the rock shaft is the clutch member 15, which is formed with a lever arm 15' extending at right angles to the shaft and having pivotal connection 15" with the pull rod 13. In its normal inoperative position, the lever arm stands in an outwardly inclined position approximately indicated by the dotted line *b* of Figure 4. The pull rod is further formed with a shoulder 16 normally spaced from the stop block 16' which latter is suitably secured to the underside of the car floor as indicated in Figure 2. This stop block is formed with a downwardly opening notch 16'', wherein the pull rod loosely slides so that when the latter is moved longitudinally the shoulder 16 will engage with the face of the block for a purpose hereinafter to be described.

The clutch member 15 is further formed with a pair of radial claws 17, adapted to interlockingly co-operate with the claws 18" of the shifting clutch member 18, the latter being formed at its opposite end with an integral collar 18'''. Thus, the two clutch members form what may be termed a claw clutch, the shifting member being provided with an internal longitudinal groove 19, (Fig. 8) and the rock shaft being provided with a spline 14''' adapted to slide in said groove. When the two members are interlocked as indicated in Figure 6, a reciprocatory movement of the pull rod 13 will

cause the rock shaft to rotate about its axis. A set screwed collar 17' secured on the rock shaft serves to maintain the clutch members in proper position.

5 Extending through an opening in the car floor as at *c* (Fig 9) and having fulcrum support 19' in the bracket 20, which is secured to the underside of the floor, is the operating lever 21. This lever is provided 10 with a pawl 21' pivoted on the lever above the fulcrum, and having connection with the blade spring 21'' secured to the lever to urge the pawl downward, and rod connection 21''' with a fulcrumed sub-lever 22 mounted 15 adjacent the handle of the main lever. Thus, operation of the sub-lever will cause the pawl to be raised as desired against the tension of the spring. The pawl in turn is adapted to engage with the teeth 22' of the 20 toothed segment 23, which latter is secured to the car floor. At its lower extremity the lever is bent outwardly and is formed at its outer extremity with a fork 24. This fork is adapted to loosely embrace the periphery and sides of the flange 18, so that when 25 the lever is moved upon its pivot the shifting clutch member will disengage the claws of the member 15, and thus render the latter rotatable on the rock shaft.

30 Secured at a suitable level above the door sill 4 to the outside of the car wall and in horizontal alinement, are the journal brackets 25 wherein is journaled the open ended tubular casing 26, which latter is of reduced diameter at its ends to form a shoulder 26'. The open end of the casing is located immediately adjacent the door opening, while the closed end thereof is formed with a bearing portion 26'' which extends 35 beyond the journal block and carries rigidly the lever arm 27, which latter extends in its normal inoperative position, in an outwardly and downwardly direction as indicated in Figure 1. The interior of the casing is of uniform size throughout its length, 40 and rectangular in cross section.

45 Adjustably secured to the rock shaft as by means of the set screws 28, is the lever arm 29, which extends outwardly and 50 downwardly in its normal inoperative position. Pivotal connecting the lever arm 27 and 29, as by means of the pivot bolts 27' and 29' respectively, is the connecting rod 30. Thus, when the rock shaft is rotated, rotary movement will be imparted to 55 the casing 26. In lateral alinement with the journal brackets 25, and secured adjacent to the door jamb 3' outside of the car wall, is the journal bracket 31, wherein is 60 journaled the bushing 31' which is internally squared similar to the casing 26.

65 Supported at its respective ends in the casing 26 and the bushing 31' is the pouch carrying hook 32, hereinafter to be referred to as the pouch hook. This hook

comprises preferably a round supporting slide bar 32 of uniform diameter, having a squared end 32' adapted to loosely slide in the interior of the casing and the bushing 31', the square end being a trifle larger 70 between its sides than the diameter of the bar.

The other end of the bar is similarly squared as at 33 to loosely fit the bushing 31', the bar being preferably provided with 75 a rubber cushion 33' immediately adjacent the bushing 33 for a purpose to be later described.

Rigidly secured to the bar immediately adjacent the rubber cushion 33' is the hook member 34 shaped after the manner of ordinary mail hooks now in use, including an outwardly and forwardly directed shank portion 34, which is adapted to engage with the pouch 35 which latter is suspended in 80 the ordinary manner upon a standard, not shown.

The squared ends of the bar 32' are sufficiently small to permit the bar to be inserted into the end of the casing by slightly tilting 85 the bar as indicated in dotted lines in Figure 1. Obviously, the pouch hook may be reversed, as is also indicated in Figure 1, so that when the train is going in the reverse direction from that indicated in the 90 drawings, the hook may be reversed to meet the requirements.

In operation when the rock shaft 14 is actuated, the hook will be elevated at right angles to the wall of the car body as indicated in Figs. 2 and 3 of the drawings. In order that the hook will always assume a horizontal position, the shoulder 16 on the pull rod 13 and the stop block 16' are provided. These parts being so located as by 100 the adjustment of the lever arm 29 that when the cam wheel 11 is actuated and the shoulder 16 is thereby brought into engagement with the stop block, any additional 105 subsequent movement of the cam wheel will be absorbed by the spring 13'. By this arrangement any variation of position of the car body during travel, relative to the track, would be compensated for, by the 110 spring 13'', the pouch hook always assuming its operative level position.

115 The delivering mechanism is also operated from the rock shaft and comprises a pair of oppositely disposed pouch ejecting members or throwing arms 36, preferably mounted on the outside of the car, each member being connected by means of a group of interconnected levers to the rock shaft 14, to be actuated thereby. The ejectors as shown, are mounted on the outside 120 of the car body one on either side of the door by means of the journal blocks 36' and 36'', said blocks being alined longitudinally of the car body to bring the journals thereof a trifle above the door sill 4. Each 125 130

ejector comprises a shank 37 slidable and rotatable in said journal blocks, and parallel with the rock shaft and slidable to extend a suitable distance beyond the door 5 jamb into the doorway.

Rigidly mounted at the inner end of the shank is the pouch receiving hook or throwing arm 37' in the form of an upwardly opening crescent and which normally rests 10 upon the door sill 4 as indicated in Figs. 1 and 4. The journal block 36'' is formed with a pair of lugs between which is mounted the lever arm 38 shown in Figure 15 of the drawings. This lever arm is formed 15 with a spline 38' which is adapted to slide in the groove or guideway 38'', extending the entire length of the shank 37. Thus, the shank is slidable in the lever arm to bring 20 the hooks 37' in proper relative position in the doorway to receive the mail bag, it being optional with the operator to slide them into the desired position to accommodate bags of varying lengths. The lever 38 forms part of the lever mechanism extending 25 from the shank 37 to the rock shaft, said mechanism including the lever arm 39 rigid on the rock shaft, the link 40 having slidable pivotal connection by means of the loops 40' and the pivot pin 39' with said lever arm 39 and by means of the pivot 39' with the lever 41 the fulcrumed lever 41 pivoted by means of the pivot 41 in the journal support 42 which latter is secured 30 to the side of the car, the link 43 having pivotal connection by means of the pivot bolt 43' with the fulcrumed lever 41, and pivotal connection with the lever 38 by means of the pivot bolt 38''. The relative position of 35 these levers, when the hooks are in pouch-receiving position, is shown in Figure 4, while the position of the parts after the pouch has been ejected is shown in dotted lines in Figure 5. It will be noted in Figure 4, that the pivot pin 39' rests in the inner end of the loops 40' when the device is 40 in its normal inoperative position.

In the event of a complete operation of the catching and delivering devices, the pivot 50 39' of the lever arm 39 will initially travel in the loop 40' to the outward end thereof, (as shown in full lines in Figure 5) without materially actuating the ejecting members but imparting initial movement to the pouch hook to bring it approximately to the 55 position indicated in dotted lines as at *d* in Figure 2. A subsequent movement of the rock shaft will move the group of levers to the position indicated by dotted lines in Fig. 5, this subsequent movement carrying 60 the pouch arm to its horizontal pouch-catching position and imparting a complete ejecting movement to the ejecting members. Thus, the loops function as means for delaying operation of the ejecting mechanism 65 relative to the actuation of the pouch hook,

to thereby effect a complete delivering operation during the final movement of the catching device. Thus, a sudden impulse is imparted to the delivering hooks 37', to throw the bag a safe distance away from the 70 track. This delay of the delivery operation permits the pouch hook to engage the suspended pouch before delivery is made, so that the delivered bag will be thrown clear of the standard upon which the pouch is 75 suspended. Thus, the danger of the thrown pouch striking the standard is avoided.

Rigid on the rock shaft, is the lever arm 44 which normally extends downwardly and inwardly and has connection with a cable 80 45, which latter runs over the sheave 46 and is attached to a counterweight 47. This weight functions together with the spring 11' to hold the rock shaft in its normal inoperative position. While we have shown 85 one form of our invention, it is to be understood that constructional changes may be made without departing from the spirit and scope of the invention.

We claim—

1. A device of the class described for railway mail coaches comprising in part in combination, a stationary member on the track located between the rails thereof, a rock shaft carried by the coach extending 95 longitudinally thereof, mechanism including a movable cam to be actuated thereby when the cam is moved, said mechanism being supported on the coach and operatively connected to said rock shaft, said cam 100 being adapted to engage with said stationary member to be moved thereby concurrently with the movement of the coach over the latter, and a pouch catching hook swingably mounted on the outside of the 105 coach and normally suspended in inoperative position and operatively connected to said rock shaft to be thereby moved into operative position when the latter is actuated.

2. A device of the class described for railway mail coaches, comprising in part, in combination, a rock shaft carried by the coach extending longitudinally thereof, actuating mechanism including a movable 115 cam, responsive to the movement of which said mechanism is actuated, said mechanism being mounted on the coach and operatively connected to said rock shaft and extending to a point adjacent one of the railway 120 tracks, pouch catching mechanism supported on the outside of the coach operatively connected to said rock shaft to be actuated thereby when said rock shaft is actuated, and a stationary member located between 125 the railway tracks in the path defined during travel by said cam, said member being of a configuration to engage with said cam to move the same to a predetermined degree out of said path and so hold it for a prede- 130

terminated period of time, for the purpose set forth.

3. A mail pouch catching and delivering device for railway mail coaches, comprising in combination, a stationary member on the railway track between the tracks thereof, a rock shaft carried by the coach extending longitudinally thereof under the door opening therein and beyond opposite sides 10 of said door opening, actuating mechanism for said rock shaft carried by the coach operatively connected to said rock shaft and extending into operative engagement with said stationary member to be actuated there- 15 by concurrently with a traveling movement of the coach over said member, mail pouch catching devices mounted on the outside of the coach and extending across the door opening therein and located above said rock 20 shaft and operatively connected to the latter to be thereby moved from its normal inoperative position to operative position, when said rock shaft is actuated, and mail pouch delivering devices including oppo- 25 sitely disposed pouch receiving members mounted to be slidable toward each other from opposite sides of the door opening respectively, said devices being operatively connected to said rock shaft to be thereby 30 actuated from their normal inoperative position through a delivering operation con- currently with the operation of said mail pouch catching devices.

4. A mail pouch catching and delivering device for railway mail coaches, comprising in combination, a stationary member on the railway track between the tracks thereof, a rock shaft carried by the coach extending longitudinally thereof under the door 40 opening therein and beyond opposite sides of said door opening, actuating mechanism for said rock shaft carried by the coach operatively connected to rock shaft and extending into operative engagement with said 45 stationary member to be actuated thereby concurrently with a traveling movement of the coach over said member, mail pouch catching device mounted on the outside of the coach and extending across the door 50 opening therein and located above said rock shaft and operatively connected to the latter to be thereby moved from its normal inop- 55 erative to operative position when said rock shaft is actuated, and mail pouch delivering mechanism operatively connected to said rock shaft to be thereby actuated from its normal inoperative position through a de- 60 livering operation concurrently with the operation of said mail pouch catching devices, 65 said delivering mechanism including pouch receiving throwing arms mounted to swing outwardly from their normal inoperative position in the door opening, and means whereby the actuation of said delivering mechanism is delayed during the initial por-

tion of the movement of said pouch catching devices for the purpose set forth.

5. A mail pouch catching and delivering device for railway mail coaches, comprising in combination a stationary member on the 70 railway track between the tracks thereof, a rock shaft carried by the coach extending longitudinally thereof under the door opening therein and beyond opposite sides of said door opening, actuating mechanism for 75 said rock shaft carried by the coach operatively connected to said rock shaft and extending into operative engagement with said stationary member to be actuated thereby concurrently with a 80 traveling movement of the coach over said member, mail pouch catching devices mounted on the outside of the coach and extending across the door opening therein and located above said rock 85 shaft and operatively connected to the latter to be thereby moved from its normal inoperative to operative position when said rock shaft is actuated, and mail pouch delivering devices operatively connected to said 90 rock shaft to be thereby actuated to effect a delivering operation concurrently with the operation of said such pouch catching devices, and manually operable clutch mechanism detachably connecting said rock shaft 95 and the aforesaid mechanism.

6. A mail pouch catching and delivering device for railway mail coaches, comprising in combination, a stationary member on the railway track between the tracks thereof, a rock shaft carried by the coach extending longitudinally thereof under the door opening therein and beyond opposite sides of said door opening, actuating mechanism for said rock shaft carried by the coach operatively 100 connected to said rock shaft and extending into operative engagement with said stationary member to be actuated thereby concurrently with a traveling movement of the coach over said member, mail pouch catching devices mounted on the outside of the 105 coach and extending across the door opening therein and located above said rock shaft and operatively connected to the latter to be thereby moved from its normal inop- 110 erative to operative position when said rock shaft is actuated, and mail pouch delivering devices operatively connected to said rock shaft to be thereby actuated to effect a delivering operation concurrently with the operation of said mail pouch catching devices, the latter including an elongated 115 horizontally disposed rotatably mounted casing of squared formation, on the wall of the coach adjacent the side of the door opening, a journal support on the opposite side of the door opening in horizontal alinement with said casing, and a pouch hook consisting in part of a bar squared at its ends to 120 loosely slide with either end in said casing, 125 130

said bar extending across the door opening and being revolubly supported in said journal support.

7. A mail pouch catching and delivering device for railway mail coaches, comprising in combination, a stationary member on the railway track between the tracks thereof, a rock shaft carried by the coach extending longitudinally thereof under the door opening therein and beyond opposite sides of said door opening, actuating mechanism for said rock shaft carried by the coach operatively connected to said rock shaft and extending into operative engagement with 15 said stationary member to be actuated thereby by concurrently with a traveling movement of the coach over said member, mail pouch catching devices mounted on the outside of the coach and extending across the door 20 opening therein and located above said rock shaft and operatively connected to the latter to be thereby moved from its normal inoperative position to operative position when said rock shaft is actuated, and mail 25 pouch delivering devices operatively connected to said rock shaft to be thereby actuated to effect a delivering operation concurrently with the operation of said pouch catching devices, and means forming part 30 of said actuating mechanism for restricting the operating movement of said catching and delivering devices to a predetermined degree, and for absorbing the excess movement of said actuating mechanism which 35 arises from the variation of relative posi-

tion between the coach and said stationary member.

8. A mail pouch catching and delivering device for railway mail coaches, comprising in combination, a stationary member on the 40 railway track between the tracks thereof, a rock shaft carried by the coach extending longitudinally thereof under the door opening therein and beyond opposite sides of said door opening, actuating mechanism for said rock shaft carried by the coach operatively connected to said rock shaft and extending into operative engagement with said stationary member to be actuated thereby concurrently with a traveling movement of the coach over the member, mail pouch 45 catching devices mounted on the outside of the coach and extending across the door opening therein and located above said rock shaft and operatively connected to the latter to be thereby moved from its normal inoperative position to operative position when said rock shaft is actuated, mail pouch 50 delivering devices operatively connected to said rock shaft to be thereby actuated to effect a delivering operation concurrently with the operation of said pouch catching devices, said actuating mechanism including a weight mounted in a manner to constantly 55 urge said rock shaft into normal inoperative 60 position.

In testimony whereof we affix our signatures.

CHRISTOPHER J. M. WEBER.
AXEL OLSON.
